UNITED STATES PATENT OFFICE.

PAUL T. WEEKS, OF CALDWELL, NEW JERSEY, ASSIGNOR TO WESTINGHOUSE LAMP COMPANY, A CORPORATION OF PENNSYLVANIA.

DOUBLE-BULB BALLAST LAMP.

Application filed June 25, 1921. Serial No. 480,487.

To all whom it may concern:

Be it known that I, PAUL T. WEEKS, a citizen of the United States, and a resident of Caldwell, in the county of Essex and 5 State of New Jersey, have invented a new and useful Improvement in Double-Bulb Ballast Lamps, of which the following is a specification.

My invention relates to control devices 10 and particularly to devices of the type known as ballast devices or ballast lamps which comprise resistance elements, having high temperature coefficients of resistance and disposed in gas that is inert with respect 15 to the resistance element.

One object of my invention is to provide a ballast device comprising two bulbs, one of which shall have a conducting element disposed therein.

Another object of my invention is to provide a ballast device, of the above-indicated 20 character, in which the bulbs shall be connected by a small capillary tube in order to prevent undue circulation of the gas between the bulbs.

Another object of my invention is to provide a device, of the above-indicated character, that shall be simple and economical in construction and reliable and effective in its 30 operation.

Ballast lamps consisting ordinarily of filaments of iron wire in atmospheres of hydrogen have been used to a considerable extent in connection with Nernst glowers 35 for counteracting the negative temperature coefficient of resistance of the glowers and have been used with other devices for maintaining a substantially constant current, notwithstanding variations in the value of 40 the supply voltage. As ordinarily constructed, these lamps have comprised a filament mounted in a small bulb somewhat like that of an ordinary incandescent lamp.

While constructing bulbs of this type, it 45 has been observed that a smaller value of current is required to heat the filament to a predetermined temperature when the lamps are on the pump and still connected to the manifold than after the lamps have been 50 sealed and removed, although the gas pressure was substantially the same in both instances.

The explanation appears to be that, when 55 the lamp is on the pump, a portion of the gas is forced out of the bulb during the ex-

pansion thereof by reason of the heated filament and that the density of the gas surrounding the filament is, therefore, reduced and tends correspondingly to decrease the cooling effect upon the filament.

In order to utilize this effect to make a sensitive ballast lamp that will operate over a relatively wide range of voltage, I provide a lamp embodying two bulbs that are connected by a capillary tube having a small bore, and dispose the resistor element within one of the bulbs.

If the value of current traversing the ordinary ballast lamp of the single-bulb type tends to increase, the voltage across the 70 terminals of the filament or resistor increases by reason of the increased resistance resulting from the heat that is developed therein, the amount of heat that is developed 75 in a filament of such a ballast lamp increases in the value of current traversing the same.

The auxiliary bulb serves as an expansion chamber and operates in a manner similar to that of the manifold mentioned above. 80 In a device of this type, as the gas is heated by the filament, it is forced from the bulb containing the filament into the auxiliary bulb. The capillary tube prevents circulation of the gas. By means of such a construction, the temperature of the gas in the main bulb will be considerably greater than the temperature of the gas in the auxiliary bulb. Although the pressure in the two 85 bulbs will be the same, the density of the gas surrounding the filament will be less than the density of the gas in the auxiliary bulb. The dissipation of heat from the filament will be correspondingly decreased by 90 reason of the decreased density of the gas surrounding the same, and a rapid increase in the temperature of the filament and in the potential difference across the terminals 95 thereof will result. The consequent increased current-regulating effect renders a 100 controlling device of this character relatively sensitive.

On one device of this type, the potential difference across the terminals of the filament increased from 1.6 volts to 3.6 volts 105 with substantially no increase in the current, whereas, in a single-bulb ballast device employing the same filament, an increase of substantially 5% of the value of current is 110 necessary to effect the corresponding in-

crease in the potential difference between the terminals of the resistor.

The single figure of the accompanying diagram is a diagrammatic view of an electrical circuit containing a control device embodying my invention.

A source 1 of energy is connected to a circuit 2 from which energy is received by a constant-current device 3. The current that 10 traverses the device 3 is controlled by a ballast-controlling device 4 to maintain the value of that current constant. The device 4 comprises a main bulb 5, an auxiliary bulb 6 and a capillary tube 7, having a small 15 bore, connected therebetween.

The bulbs 5 and 6 contain a relatively inert gas, such as hydrogen or nitrogen, and the bulb 5 also has disposed therein a filament resistor 8 of conducting material having a relatively high temperature coefficient of resistance.

It is evident that the characteristics of a device of this type will be largely affected by the relative sizes of the two bulbs, the 25 relation between the dimensions and the shape of the bulbs, the size and length of the filament and other similar features.

My invention contemplates, however, the control and regulation of a circuit by decreasing the density and, consequently, the 30 heat-transferring ability of a gas surrounding the filament when the same is traversed by a predetermined value of current in order to effect a relatively rapid increase in a 35 temperature of the filament for the corresponding value of current.

My invention is not limited to the specific structure or to the specific arrangement of the various elements, since modifications 40 may be made therein within the spirit and scope of the invention, as set forth in the appended claims.

I claim as my invention:—

1. A controlling device comprising a bulb 45 containing a conducting element of a relatively-high temperature coefficient of resistance and fluid and means whereby the density of the fluid surrounding the conducting element may be varied.

50 2. A controlling device comprising a bulb containing a conducting element and fluid and means whereby the density of the fluid surrounding the conducting element may be automatically varied in accordance with the 55 temperature of the element.

3. A controlling device comprising a bulb containing a conducting element and fluid and means whereby the density of the fluid surrounding the conducting element may be 60 automatically varied in accordance with the temperature of the fluid.

65 4. A controlling device comprising a chamber containing a heat developing member, a fluid surrounding the member and an auxiliary chamber adapted to receive a

portion of the fluid normally surrounding the heat developing member.

5. A controlling device comprising a chamber containing a heat developing member, a fluid surrounding the member and 70 means adapted to receive a portion of the fluid normally surrounding the heat developing member.

6. A controlling device comprising a chamber containing a heat developing member, a fluid surrounding the member and an auxiliary chamber to receive a portion of the fluid normally contained in said first mentioned chamber to effect a reduction in the density of the fluid surrounding the 80 heat developing member.

7. A controlling device comprising a chamber containing a heat developing member, a fluid surrounding the member and 85 means for controlling the density of the fluid surrounding the heat developing member in accordance with the temperature of that member.

8. A controlling device comprising a chamber containing a heat developing member, a fluid surrounding the member and means for controlling the density of the fluid surrounding the heat developing member in accordance with the temperature of the fluid.

9. A controlling device containing a main chamber, an auxiliary chamber, an element in said main chamber having a high temperature coefficient of resistance, a gaseous environment within said chambers and 100 a capillary communication between said chambers whereby when said element is heated the density of said gas surrounding the element will become less than the density of the gas in the auxiliary chamber and 105 effect a decrease in the dissipation of heat from said element.

10. A controlling device comprising a bulb, a current-heated member therein, a fluid surrounding the member and means 110 associated with the bulb whereby the current-heated member may control the conditions within the bulb.

11. A controlling device comprising a receptacle, a current-heated member therein, a fluid surrounding the member and means for controlling the relative heating of the current-heated member by different values of current.

12. A controlling device comprising a receptacle, a current-heated member therein, a fluid surrounding the member and means for controlling the cooling effect of the fluid.

13. A controlling device comprising a bulb, a current-heated member therein, a fluid surrounding the member and means for controlling the heat-transferring capacity of the fluid.

14. A controlling device comprising a bulb, a current-heated member therein, a 130

fluid surrounding the member and means for decreasing the heat-transferring capacity of the fluid as the temperature of the heated member increases.

5 15. A resistance device comprising a gas filled bulb containing a filament and connected to another bulb by a capillary portion whereby a portion of the gas is forced from the first bulb into the other one when 10 the filament is heated.

16. A resistance device comprising a hydrogen filled bulb containing a resistance element and connected to another bulb by a capillary tube whereby some of the gas in 15 the first bulb flows into the other bulb, thereby decreasing the density of the gas in the first bulb, when the resistance element is heated.

17. In combination with a device requiring a substantially uniform current, a controlling device comprising two bulbs connected by capillary means.

18. In combination with a device requiring a substantially uniform current, a controlling device comprising two bulbs connected by a capillary tube and an electrical conducting member disposed in one bulb.

19. In combination with a device requiring a substantially uniform current, controlling means comprising a fluid filled bulb 30 containing a conducting element and means serving as an overflow reservoir for the fluid when the conducting element is heated.

20. In combination with a device requiring a substantially uniform current, controlling means comprising a bulb containing a conductive filament surrounded by a fluid and means whereby the density of the fluid surrounding the conductive filament may be 35 automatically varied when the filament becomes heated.

21. In combination with a device requiring a substantially uniform current, a ballast resistance comprising a chamber filled 40 with the fluid and containing a heat

developing member in series with the device and means controlling the density of the fluid in accordance with the temperature of the heat developing member.

22. In combination with a device requiring a substantially uniform current, a resistance device comprising a bulb, a filament therein, a fluid surrounding the filament and means associated with the bulb for modifying the heat losses from the filament when 55 the same is heated.

23. In combination with a device requiring a substantially uniform current, a ballast resistance comprising a gas filled bulb enclosing a current-heated resistance member and means for controlling the heat transferring capacity of the gas according to the 60 temperature of the heated member.

24. In combination with a device requiring a substantially uniform current, a ballast resistance comprising two vessels having an environment of a given substantially uniform density, a resistance element in one of said vessels in series with said device and a capillary communication between said 70 vessels whereby the density of the environment in the two vessels becomes unequal when said resistance element raises the temperature of the environment within one of said vessels.

25. In combination with a device requiring a substantially uniform current, a ballast resistance in series therewith comprising a lower bulb containing a resistance element and connected to an upper bulb by a 80 capillary tube which prevents circulation of a fluid in said bulbs whereby, when the device is operated, the fluid in the lower bulb is at a higher temperature and of a lower density than that in the upper bulb. 85

In testimony whereof, I have hereunto subscribed my name this 10th day of June 1921.

PAUL T. WEEKS.
